GAME OF SKILL

John Brady, Baltimore, Md.

Application December 16, 1933, Serial No. 702,784

12 Claims. (Cl. 273—86)

This invention relates to a game of skill in which racing figures allotted to the contestants are made to travel along a race course, their progress being controlled by the striking of targets by the contestants, so that the contestant exhibiting the best marksmanship will bring his racing figure to the finish line first.

In one form of the invention the racing figures, which may be horses and jockeys, for example, are driven along parallel paths and are stopped at certain positions along the path, for instance, at hurdles; whereupon each contestant whose racing figure has stopped shoots at an individual target by which his figure is controlled and if he hits the target the figure starts on its way again.

One object of the invention is to avoid complexity in the construction and operation of a device of the kind described, as far as possible.

Means are preferably provided to impart to the racing figures realistic movements simulating those of their natural counterparts, as they travel along the race course.

The device may be arranged so that when any figure reaches the finish line it stops all the other figures and actuates an indicator to show which figure won.

The targets may be provided with means for modifying their effective surface in order to adapt them to the relative skill of the contestants, instead of placing the contestants at different distances from the targets.

The invention will be explained with reference to the accompanying drawings showing one form in which it may be carried out. In the drawings, Fig. 1 is an isometric view showing the general layout of a device made according to the invention.

Fig. 2 is a somewhat diagrammatic horizontal section showing the track and switch system,

Fig. 3 is a vertical section on the line 3—3 of Fig. 2,

Fig. 4 is a vertical section on the line 4—4 of Fig. 3,

Fig. 5 is a detail side view of one of the racing figures and its carrier,

Fig. 6 is a section on the line 6—6 of Fig. 5,

Fig. 7 is a detail perspective view of one of the target controlled switches,

Fig. 8 is a rear view of the range control device of one of the targets, and

Fig. 9 is a vertical section on the line 9—9 of Fig. 8.

The embodiment of the invention shown in the drawings is one in which the racing figures represent horses and jockeys and are controlled

by target devices intended to be shot at by rifles. Any other kinds of figures and any other means for striking the targets may be used. In Fig. 1, 10 is an enclosure for the race course, inside of which at some elevation from the floor 11 is a 5 platform 12. The racing figures, one of which appears at 13, travel from the right end to the left end of the platform 12 along parallel paths. Any suitable means may be employed to carry and drive the figures, so long as it permits the 10 motion of each figure to be controlled independently of the others. Thus a common driving means may be employed for all, with means for individually connecting and disconnecting the figures. In the form of the invention shown in 15 the drawings, each racing figure is supported on a frame 14 pivoted to a truck (Fig. 3) driven by an electric motor 19. The frames travel along slots 16 in the platform 12, so that only the figures and the upper part of the frame appear above the 20 platform, the driving mechanism being concealed from view. Arranged at intervals along the platform 12 are a series of hurdles 17 and means are provided to stop each racing figure as it reaches a hurdle. A row of targets at 160 numbered 1, 25 2, 3, 4 and 5 is arranged along the front wall 18 of the enclosure 10 and these targets control the stopping means for the racing figures in such a way that if a contestant strikes the target in front of him his racing figure starts on its way again. 30 At a distance in front of the targets is a bench 20 behind which the contestants stand. Each contestant is supplied with one of the rifles 21. The targets may be made to disappear when struck and to reappear in ready position coincident with the stopping of the horses at the hurdles. The numbers 1, 2, 3, 4, 5 of the targets are preferably on detachably mounted plates 9 so as to be interchangeable.

Any suitable system of tracks may be provided 40 for the trucks carrying the racing figures to travel upon. In the drawings I have shown a track system in which individual parallel tracks forming the race course proper all lead to and branch from a common return track, which has the advantage of conserving space and making it possible easily to switch the racing figures onto different tracks. The parallel tracks of the race course proper are designated respectively 25A, 25B, 25C, 25D and 25E, while the common return track is designated 33. Five tracks and racing figures are shown, but this number may be increased or decreased as desired. The direction of travel of the figures is from right to left along the race course and from left to right along the 55

return track. At the right end the individual tracks 25A, 25B, etc., branch out from the ladder track 34 and switches 35A, 35B, 35C, and 35D controlled by buttons 36A, 36B, 36C, and 36D are provided to switch the trucks onto their respective tracks on the race course. If all the switches are open the truck travels onto the track 25E.

In designating the tracks of the race course and associated elements, I have used the letters A, B, C, D, and E together with a reference numeral 10 to indicate a particular track or associated element, but in some cases the letters are omitted, where the parts are referred to collectively or representatively.

15 The electric circuits for driving the motors of the trucks on which the figures are carried may be of any suitable kind, the one shown in the drawings being very satisfactory because of its simplicity and its adaptability to the purpose. It 20 is desirable to have the circuits arranged so that the figures can be started simultaneously and stopped simultaneously at the finish of the race. Also, it should be possible to stop and start the figures individually during the race. It should 25 also be possible after the finish of the race to run the trucks carrying the figures individually onto the return track to avoid collisions and to enable the operator to switch them onto their several tracks at the starting end of the course.

30 In the embodiment of the invention shown in the drawings, electric current for driving the trucks 15 is derived from a transformer 29 connected by wires 30 with main wires 31. One terminal 28 of the transformer is connected by 35 wires 27 and 26 with the rails, all of which are in constant electrical connection. The other terminal 55 of the transformer is connected through wire 58, main switch 57 and wire 56 to a bus bar 54; from which separate wires 53A, 53B, 40 53C, 53D, and 53E lead off to switches 46A, 46B, 46C, 46D, and 46E arranged respectively beside the tracks 25A, 25B, 25C, 25D, and 25E. From the switches 46 wires 45A, 45B, 45C, 45D, and 45E lead to third rails 40A, 40B, 40C, 40D, and 45 40E.

45 Each truck carries a brush 42 (Fig. 3) making contact with the third rail, to lead the current to one terminal of its motor 19, the other terminal being grounded to the wheels of the truck. The main switch 57 is for starting and stopping all of the trucks at the same instant at the start and finish of the race. The switches 50 46 are for stopping and starting trucks individually during the race, and also for manipulating the trucks separately when running them onto the return track. In addition to the connection through main switch 57, bus bar 54 can also be connected with terminal 55 of transformer 29 through a parallel circuit consisting of wires 61 and 59 and switch 60. The third rail 40R of the return track 33 is connected to terminal 55 of the transformer 29 through wires 62 and 63. A resistance 64 may be inserted in wire 63 for a purpose to be presently described. Third rail 40R is connected by bridge wires 37 with third rails 42A, 42B, 42C, 42D, and 42E at the finish end of the tracks 25, the third rails 42A, 42B, etc. being separated from third rails 40A, 40B, etc. by gaps or insulating sections 38. In the same way at the starting end of the tracks 25 third rail 40R is connected by bridge wires 37 with third rails 41A, 41B, 41C, 41D, and 41E, these third rails being separated by gaps or insulating sections 39 from third rails 40A, 40B, etc. Thus it will be seen that the third rail 40R and the 65 third rails 42 and 41 are constantly connected

5 to the transformer 29, whereas third rails 40A, 40B, 40C, 40D, and 40E are dependent upon either one of switches 57 or 60 being closed, and also upon their respective switches 46 being closed.

Any suitable means may be used to close the main switch 57 at the start of the race and to open it at the finish. In the drawings switch 57 is shown as having a stationary contact 74, to which wire 58 is connected, and a three-armed 10 movable contact 75, 76, 77, to which wire 56 is connected. The arm 75 closes the circuit to contact 74. The arms 76 and 77 are lever arms for operating the switch. Arm 76 is connected by a link 73 to a series of bell crank trip levers 70 15 located at the finish line, one being placed beside each track 25. These trip levers have arms 71 which extend across the tracks in one position and move clear of the tracks in another position, and arms 72 connected to the link 73. When 20 the arms 71 extend across the track the main switch 57 is closed. When the arms 71 are moved clear of the track, as when any one of the trucks travels past the finish line, the main switch 57 is opened. 25

The main switch 57 can also be operated by hand to start the race. For this purpose the arm 77 of the main switch is connected through a link 78, a bell crank lever 79, a link 80, and a bell crank lever 81 to the shaft 82 of a starting button 83. The main switch 57 can be opened and closed at will by the button 83. In order to line up the racing figures at the starting post stop bars 101 may be provided and connected to link 80 of the starting mechanism by 30 lever arms 100. The stop bars are arranged so that when the main switch is open the stop bars extend across the tracks, and when the starting button 83 is pulled out to close the main switch 35 the stop bars swing clear of the tracks. 40

The individual switches 46 which stop the racing figures during the course of the race may be operated in any desired manner. As shown in the drawings they are operated by trip levers arranged in position to be engaged by the trucks 45 as they pass by on the tracks 25. Each switch 46 has a swinging arm 52 pivoted at 49 to a support 44. Two contact plates 43 and 48 are bridged by a contact bar 32 fixed to, but insulated from the arm 52. Contact 48 is made of 50 springy metal and bulges up into the path of bar 32. Wire 45 is connected to contact plate 48 and wire 53 to contact plate 43. Two other arms, 50 and 51, are rigidly connected to arm 52. Contact plate 43 is insulated from pivot 55 post 49 and the movable switch element 50, 51, 52 by a fiber bush 47. Arm 50 serves as a trip lever; when the switch is closed the arm 50 extends across the track and when arm 50 is moved aside by the truck passing by on the track the 60 switch is opened. Additional trip levers are arranged at intervals along the tracks. These are all connected by a link 67 to the switch arm 52. Each trip lever is in the form of a bell crank with one arm 66 connected to link 67 and the other arm 68 extending across the track, or clear of the track, according to whether the switch 65 46 is closed or open. When any one of the trip levers 66, 68 is moved clear of the track it throws open the switch 46, thereby cutting off the current from the third rail of that track. The circuits of the other tracks are unaffected. At the starting end of the tracks the four trip levers 66, 68 and the one switch 46B are mounted somewhat differently from the trip levers and 70 75

switches further down the track. Instead of being pivoted on a stationary post 49 they are fixed to the top of a spindle 49X rotatably supported in a bearing 65 (Figs. 3 and 4). Spindle 5 49X extends through the upper floor 24 and carries at its lower end a fixed arm 69 connected to the shank 22 of a button 23 which serves to operate the switch 46 individually by hand. There is a button 23 for each switch 46.

10 The individual circuits to the truck motors are preferably opened by the trucks themselves as they arrive at certain points along their tracks, and each circuit is preferably closed again by a target device allotted to the contestant playing 15 the racing figure on the track corresponding to that circuit. The target devices may be of any desired construction for this purpose. The drawings show a target device having a striking plate 84 mounted upon a support 85 pivoted at 20 86 and counterbalanced by a weight 87. The support 85 is connected by a link 88 to arm 51 of switch 46. The striking plate 84 is visible through an aperture 160 in the front wall 18 of the enclosure 10. When switch 46 is open 25 the striking plate 84 of the target is close to the opening in wall 18 and clearly visible. When the striking plate is hit it moves back from the opening, shifting switch 46 to closed position. The arrangement may be such that the target 30 is clearly visible when the switch is opened, but not when the switch is closed, so that the appearance of the target in ready position gives a visible signal to the contestant that it is time to fire.

35 I prefer to provide means for changing the effective surface of the striking plates of the target devices, so that handicaps can be arranged without making some of the contestants stand further from the targets than others, thus 40 avoiding the danger of having some within the range of the guns of the others and also reducing the space required. One means for accomplishing this result is illustrated in Figs. 8 and 9. In the front wall 18 of the race track 45 enclosure, which may be of bullet proof sheet metal, there is an aperture 161 for each target, which may be square and is at least as large as the greatest effective area to which the target devices may be adjusted. Mounted on the back 50 of the wall 18 is a plate 162 having an aperture 163 conforming to the aperture 161, this plate serving as a base plate for mounting the adjustable mechanism. Two channel bars 164 and 165 are secured to the back of plate 162 in parallel 55 relation, with the channels opening toward each other. Slidably supported in the channels are cover plates 166 and 167 arranged one behind the other in overlapping relation. The adjacent edges of these cover plates have notches 158 and 159 the sides of which are 90° apart and are arranged so that the two notches form a square opening, 160, which is the effective aperture through which the bullets must pass to hit the striking plate 84. Thus as the plates are 60 moved to overlap more, the size of the square opening decreases. The square opening formed by these notches is located in line with the openings 161, 163 and directly in front of the striking plate 84 of the target when the latter is in forward position. The plates 166 and 167 are bullet proof and therefore prevent any bullet from striking the plate 84 of the target except one passing between the sides 158, 159 of the square opening 160.

75 Any suitable means may be provided for mov-

ing the plates 166 and 167 to adjust the size of the opening 160. The drawings show four rack bars 170 secured to the backs of the plates 166 and 167 adjacent the ends of the plates which are guided in the channels 164 and 165. Two gears 5 171 and 171a rotatably mounted on shafts 172 engage the rack bars 170 on plate 167; while two gears 173 and 173a rotatably mounted on shafts 174 engage the racks 170 on plate 166. The gears 171 and 171a are connected together by a link 10 175 so as to rotate in the same direction to an equal extent. The gears 173 and 173a are similarly connected together by a link 176. Gear 171 is connected to gear 173 by two pinions 178, so that these two gears rotate in opposite directions. 15 Thus any rotation of gear 171 will be accompanied by an equal rotation in the same direction of gear 171a tending to move both ends of plate 167 in the same direction, while a corresponding rotation in the opposite direction will be im- 20 parted to gears 173 and 173a tending to move plate 166 in the opposite direction to the movement of plate 167. Gear 171 is connected by a pinion 180 to a gear 181 fixed to a shaft 179, which extends through the base plate 162 and 25 front wall 18. On the front end of shaft 179 is fixed a pointer 182, the end of which travels over a scale 183. The scale 183 may be graduated in yards indicating the comparative distances represented by the sizes of the opening 160, with 30 reference to a standard target.

The racing figures are preferably made to simulate those which they represent as nearly as possible, both in appearance and in movements. In the case of a horse and jockey I have found 35 that this can be accomplished very well in the manner shown in detail in Figs. 5 and 6. The upper end of support 14 is fixed to the body 109 of the jockey by a rivet 110 and a pivot 111, the latter serving to connect the body of the jockey 40 to the body 112 of the horse. The extremities of the horse, its legs 113 and 114 and its head 115, are pivoted to the body 112 by rivets 116. The arms 117 of the jockey are pivoted at 118 to the horse's head and the legs of the horse are connected to the lower end of the body of the jockey by links 119 and 120. The horse is balanced so that its center of gravity is under the pivot 111 and its body 112 therefore retains a substantially horizontal position. If the body 109 of the jockey 45 is rocked, there is a relative angular movement between horse and jockey about the pivot 111, and the arms 117 and links 119 and 120 cause the extremities of the horse to execute movements simulating those of a horse galloping. The rocking of the body 109 of the jockey is preferably 50 derived from the mechanism shown in Figs. 5 and 6. Frame 14 is pivoted on truck 15 at 125. Below the platform 12 the frame 14 is of triangular shape and carries at its rear angle a roller 126. 55 This roller travels upon an elongated undulating cam 127 extending along the track. As the truck travels along the track the roller 126 rides up and down upon the waves of cam 127, rocking the frame 14 and imparting an up and down 60 movement to the horse and jockey. At the same time it imparts an angular movement to the jockey which causes the head and legs of the horse to move up and down and in and out, since the body 112 of the horse tends to retain 65 a horizontal position. The cam 127 has small hills 128 between the hurdles and large hills 129 at the hurdles. The horse therefore has movements simulating those of a galloping horse between the hurdles and a jumping horse at the 70 75

hurdles. While the frame 14 passes through gaps 130 in the hurdles, the horse appears to jump over the hurdles, to one viewing him from the side. When the horse passes the finish line 5 roller 126 rides off cam 127, which ends at this point, and the base of the triangular frame 14 comes to rest upon cross piece 121 of the truck 15. In order to simulate the prancing of the horses at the starting post there may be provided a shaft 135 carrying eccentric disks 136 upon which rollers 126 rest when the horses are in starting position. The shaft 135 may be driven by an electric motor 137 (Fig. 2) receiving its current from wires 62 and 27.

15 A barrier 140 may also be arranged at the starting position. As shown in the drawings, this barrier consists of a cross-bar mounted upon arms 141 pivoted on bearing posts 142. Rearward extensions 143 of the arms 141 are connected by links 144 to arms 145 fixed to a shaft 146 pivoted in bearing posts 147, the shaft 146 extending under the tracks from one side to the other and forming a rigid connection between the arms 145. The arm 145 on the near side in Fig. 3 20 has rigidly connected to it an arm 148 having at its upper end a slot 149 embracing a pin 150 on the shaft 82 of starting button 83. When the starting button 83 is pulled out, arm 148 is pulled back and links 144 are pulled down, thus raising 25 the barrier bar 140. This barrier has no mechanical function, but is merely intended to make the device more realistic.

An indicator may be provided, as shown at 90 (Fig. 2), for instance, in the form of a box having 30 windows 91 corresponding to the several tracks, the windows to be illuminated selectively by the trucks reaching the finish line. The glasses of the windows, each of which bears a number 1, 2, 3, 4, or 5, are hung by detachable devices 89 35 so that their positions can be easily interchanged. For controlling the illumination of the windows 91, there may be beside each track at the finish line a switch 92 comprising a stationary contact 93, a movable contact 94, and a trip arm 95 to 40 be actuated by a truck passing by on the track. The contacts 93 and 94 are connected by wires 96 and 97 to the corresponding bulb (not shown) behind the window allotted to the particular switch. Electric current for lighting the bulbs 45 of the indicator is conducted through wires 98 and 99 leading to wires 27 and 62 connected to the terminals of the transformer 29.

The operation of the device is as follows:

At the start of the race the various switches, 50 trip levers, and stops are in the position shown in Fig. 2. The barrier 140 is down and the eccentrics 136 are causing the horses to prance in readiness for the start. Buttons 23 are now pushed forward to bring the trip lever 68 and 55 switch arms 50 across the tracks in position to be struck by the trucks. The main switch 57 stands open and the finish trip bars 71 are clear of the tracks. The circuits for all of the tracks are closed, except for the main switch 57. The 60 targets are moved back from ready position as the bars 68 and 50 on the trip levers and switches are brought across the tracks. The contestants stand ready with gun to shoulder. The race is started by pulling out starting knob 83. This 65 removes the stop bars 101 from the tracks, raises barrier 140, and closes main switch 57. The horses start and move forward at the same speed, all stopping at the first barrier when they move the trip levers 68 and 50 and open the switches 70 75 46. This movement of the switches is accom-

panied by a movement of the striking plates 84 of the target devices forward to ready position. The contestants commence firing at their respective targets. When a contestant strikes his target the target swings back and closes switch 46, 5 which completes the circuit to the motor of his horse and the horse jumps the hurdle and proceeds down the track. At the next hurdle it strikes a trip lever 68 or 50 and opens the switch 46 again. This sequence continues until the 10 horse jumps the last hurdle and proceeds down the final stretch. The first horse to cross the finish line strikes the trip arm 71 which stands across his track and throws open the main switch 57, thus stopping all the horses wherever they 15 may be. The first horse to finish also trips his switch 92 and illuminates the corresponding window 91 of the indicator 90.

The race being finished, the horses are now to be brought around to the starting post again. 20 The operator will bring the horses one after another onto the return track, which will return them to the starting end, the switches 35 being controlled so as to bring each horse onto the desired track at the starting end, which may or 25 may not be the track on which it traveled in the preceding race. There may be a call for shifting of the horses to different tracks, for a change of luck, or whatnot. It is for this reason that the window glasses 91 and number plates 9 are 30 detachably mounted, so that their positions can be interchanged as the horses are shifted from one track to another. The numbers on the window glasses 91 and plates 9 correspond to the numbers on the horses. 35

Suppose the first horse to finish was the one on track 25A. The operator now pulls out all of the knobs 23, thus opening all of the circuits to third rails 40-40E. Thereupon switch 60 is closed, but this has no effect because the circuits are all 40 open at the switches 46. Now the button 23A is pushed in, closing the circuit of the track 25A and starting the horse on that track toward the return track. When the horse reaches the third rail 42A it continues its travel around the return 45 track without regard to the position of switch 46, since the third rails 40R, 41 and 42 are in constant connection with the transformer 29. Resistance 64 is inserted in wire 63 to reduce the voltage at the third rail of the return track, to 50 compensate for the reduction in the drag on the motor after the roller 126 leaves cam 127, which it does at the end of track 25. When the horse reaches the ladder track 34 it may be switched onto the same track 25A again, by pushing in 55 button 36A, or it may similarly be switched onto any other track. The horse proceeds until the brush 42 of its motor passes gap 39 and comes onto third rail 40A, at about which time the front wheels of the truck strike against stop arm 101 60 and the operator cuts off the current to the motor by pulling out button 23A and opening switch 46A.

Now the button 23 of any other track, say 23B, is pushed in and the horse on track 25B starts 65 toward the return track. Since the finish trip arms 71 are all clear of the tracks, there is no interference at this point with the progress of the horse. It is for this reason that the additional switch 60 is provided as a substitute for 70 the main switch 57 in returning the horses to the starting position. The horse proceeds around the return track to the starting end and is there switched onto any desired track.

In switching horses from one track to another 75

there will be two horses on the same track at one stage of the procedure. Thus if the horse from track 25A is switched onto track 25B, the horse which started on track 25B may still be there. However, there will be no difficulty in bringing the horse which started on track 25B onto the return track, for even though the current is switched onto the motors of both horses, the horse just coming onto track 25B will be restrained by the stop arm 101 and its wheels will turn idly until the other horse reaches the return track, at which time the button 23B can be pulled out to open the circuit to third rail 40B. In order to avoid unduly long operation of the motor of a horse held by a stop arm 101, the horses can all be manipulated in such a way that they are close to the gaps 38 before any one is sent onto the return track, in which case a mere touch of the switch 46 will serve to send any horse onto the return track.

It will be evident that the invention covers many modifications of the illustrative form of it shown in the drawings. Any kinds of figures having sufficient interest for a race may be substituted for horses and jockeys. The invention is not confined to electrical operation, though I regard that as the most satisfactory source of power. Various other ways of controlling the progress of the racing figures by means of target devices may be substituted for the one shown. Many of the details shown are not essential.

Having described my invention,

I claim:

1. In a device of the class described, a movable figure, means for driving said figure, means for starting and stopping said driving means, and a target device controlling said starting and stopping means, said starting and stopping means being movable by said figure to stopping position and by said target device to starting position.

2. In a device of the class described, a simulative figure, a carrier for said figure, electrical driving means for said carrier, a circuit for said driving means, a switch to open and close said circuit, means operated by said carrier for opening said switch, and a target device adapted to close said switch.

3. In a device of the class described, a movable figure, electrical driving means therefor, a circuit for said driving means, a switch to open and close said circuit, and a target device connected to said switch, said switch, when closed, being in position to be engaged by said figure to open the same, said target device being adapted to close said switch when struck.

4. In a device of the class described, a race course; a figure adapted to travel along said course; driving means for said figure; stopping and starting means for said driving means arranged at intervals along said course and operable by said figure to stop said driving means; and a movable target device connected with said stopping and starting means so as to be moved into "ready" position when said stopping and starting means is operated by said figure, said target device being adapted to move under the impact of a missile to shift said stopping and starting device to start said driving means.

5. In a device of the class described, a plurality of figures; means for driving said figures along individual parallel courses; means for separately interrupting the drive of each figure as it reaches certain positions along its course; a plurality of target devices correlated respectively with said figures, each provided with means for

varying the size of the effective surface thereof; and means whereby each target device, when struck, restores the drive to the figure correlated therewith.

6. In a device of the class described, a plurality of figures; means for driving said figures along individual parallel courses; means for separately interrupting the drive of each figure as it reaches certain positions along its course; a plurality of target devices correlated respectively with said figures, each of said target devices comprising striking plates partially covered by adjustable guard plates adapted to expose only a predetermined, but variable extent of surface of each striking plate; and means whereby each target device, when struck, restores the drive to the figure correlated therewith.

7. In a device of the class described, a plurality of figures; means for driving said figures along individual parallel courses; means for separately interrupting the drive of each figure as it reaches certain positions along its course; a plurality of target devices correlated respectively with said figures, each of said target devices comprising striking plates partially covered by adjustable guard plates adapted to expose only a predetermined, but variable extent of surface of each striking plate; range indicators connected to said guard plates and adapted to be adjusted to indicate the range corresponding to the extent of surface exposed by said guard plates; and means whereby each target device, when struck, restores the drive to the figure correlated therewith.

8. In a device of the class described; a plurality of parallel tracks; a plurality of electric motor trucks adapted to travel on the respective tracks; independent electric circuits associated with the respective tracks for supplying current to the motors of said trucks; switch controlling devices arranged at intervals along each track; each of said circuits including a switch, said switches being adapted to be opened by the switch controlling devices along the respective tracks with which they are associated; and a plurality of target devices, one for each track, adapted to close the respective switches when struck.

9. A device as described in claim 8, in combination with a master switch device adapted to open all said circuits and comprising means whereby it can be operated by any one of said trucks reaching a certain position along its track.

10. A device as described in claim 8, in combination with a single return track into which all of said parallel tracks lead, and switches for leading said trucks from said return track to their respective parallel tracks.

11. In a race course device, a plurality of figures representing horses and jockeys, means for driving said figures along parallel courses, means for causing said figures as they travel to execute movements simulating their natural counterparts, hurdles arranged at intervals along said courses, means for arresting the travel of each figure at each hurdle along its course, and target controlled means for setting said figures in motion again.

12. A race device as described in claim 11, in combination with a barrier device for starting said figures, and means for causing said figures as they stand at the barrier to execute movements simulating the prancing of horses at the barrier.
